UNITED STATES PATENT OFFICE.

OSCAR J. CHARLES, OF FORT MCPHERSON, GEORGIA.

FIELD STOVE, OVEN, RANGE, AND THE LIKE.

1,141,934.

Specification of Letters Patent.

Patented June 8, 1915.

Application filed October 25, 1913. Serial No. 797,337.

To all whom it may concern:

Be it known that I, OSCAR J. CHARLES, a citizen of the United States of America, and a resident of Fort McPherson, county of 5 Fulton, and State of Georgia, have invented certain new and useful Improvements in Field Stoves, Ovens, Ranges, and the like, of which the following is a specification.

The main objects of this invention are to 10 provide certain improvements in stoves, ovens and ranges, particularly those adapted for use in military encampments; to provide an improved arrangement and structure of the fire box and combustion chamber 15 thereof adapted for durability and efficiency; to provide an improved incinerating member adapted for use in connection with the range proper; to provide adjustable controlling means adapted to direct the flow of 20 the gases of combustion either through the oven or stove member or through the incinerating member as desired; to provide a device of this kind adapted for assembling and use directly on the ground in connection 25 with supplementary trenches provided in the ground thereunder, or in a base structure; and to provide a knock-down range of 30 this character adapted to be readily set up for use, and to be packed in small space for transportation and storage.

The present invention is to some extent a modification and improvement of the apparatus described and claimed in my United States Patent No. 1,056,259, issued March 18, 35 1913, on incinerators.

An illustrative embodiment of this invention, together with certain modifications, is shown in the accompanying drawings, in which—

40 Figure 1 is a front elevation of an ordinary field range fitted with attachments so as to embody the present invention, the parts being shown in position for service; Fig. 2 is a reduced perspective view of the 45 range and its attachments knocked down and packed to occupy a minimum of space; Fig. 3 is a perspective view of the incinerator member in its telescoped condition; Fig. 4 is a broken top plan view of the device 50 with its parts in the position shown in Fig. 1; Fig. 5 is a perspective view of a range illustrating this invention; and Fig. 6 is a broken side elevation of the range shown in Fig. 5.

55 In the form shown, the heat utilizing

member, or oven proper, designated by the numeral 1, may be of any usual or desirable form. The top is closed, with the exception of a flanged opening 5 for the smoke pipe or stack 6. It has a door 7 in its front wall 60 through which access may be had to the cooking compartment in the interior. The oven comprises a double wall having passages or flues, not shown, for the hot gases of combustion. The internal construction 65 need not be further described herein as it may be of usual form and the features thereof are not herein claimed.

In accordance with the present invention the rear wall of the oven 1 is open at its 70 lower part to provide an inlet 2 through which flame and products of combustion are admitted to the said gas flues in the interior of the oven. The upper part 3 of said wall serves as a baffle plate to retard somewhat 75 the rush of gases from the combustion chamber into the said gas passages.

In the form shown an L-shaped casing made up of sections 8, 9 and 10, is detachably connected to the rear end of the stove 80 or oven 1, and communicates with the said gas inlet 2. It extends across the rear and forwardly along one side of the oven, and the sections thereof are detachably fastened together in such manner as to form substantially tight joints. They are so shaped that their abutting edges overlap and interfit, and they may be fastened together by any suitable means, permitting of their ready 85 separation, such for instance as the pivoted latch arm 14 illustrated in Fig. 4. This casing 10 is of inverted channel or U-shape in cross section and is of comparatively shallow depth. It is open at the bottom and is adapted to be used as a covering for a trench 15 which constitutes the lower portion of a firebox or fuel burning compartment under the forward casing section 10 and combustion chamber under the transversely disposed rear sections 8 and 9. The 90 inner wall or flange of section 10 is disposed substantially against the adjacent side of the oven member.

The front of the casing 10 is provided with a hinged fuel door 16 which may serve 105 to partially control the admission of air. The top of the said cover member 8, 9 and 10 is substantially level so that the flow of gases is retarded sufficiently to insure substantially complete combustion of the gase- 110

ous parts of the fuel before delivery to the oven, and also so as to present a level surface or stove top adapted to receive cooking utensils. The said cover sections are commonly known as "boiling plates." In the top of the L-casing there may be provided one or more openings 17 for the purpose of receiving pots or kettles, as shown in section 10 of Fig. 4. Such openings may be closed by any suitable means, as a cover of sheet metal, not shown.

The incinerator member is adapted for disposition beneath the oven to receive the flame and gases from the combustion chamber at times, and comprises a long rectangular box 19, 20, 21 composed of sheet metal plates joined together, the same being welded or otherwise made tight, rendering the box fire and waterproof, closed centrally and provided with an opening 24 at the rear end on its upper side for the entrance of flame and gases of combustion. The forward end is also provided with an opening 25 on its upper side, a closure therefor being provided consisting of a cover 26 having a handle. Adjacent to the forward end is a lateral opening 28 adapted to serve as a discharge passage for the gases and products of combustion. This opening is preferably provided with a suitable flange adapted for the attachment of a stack 30. In order to facilitate transportation and storage of the incinerator box it is made in detachable sections adapted to telescope one within another. Adjustable means are provided adapted to control the direction of flow of the products of combustion either through the oven and stack 6, or through the incinerator and its stack 30. For this purpose dampers 31 and 32 are disposed in any convenient arrangement adapted to facilitate operation, and may be conveniently placed and easily controlled in the said stacks respectively as shown.

When it is desired to set up this improved range for service a U-shaped trench is first dug in the ground, one side of which together with the transverse portion, is substantially uniform in depth and adapted to serve as the bottom and main body portion of a fire box and combustion chamber, preferably of a size adapted to receive ordinary cord wood. The opposite arm of the trench is dug somewhat deeper at its inner end and is formed to incline upward to the surface toward its front end. The incinerator box is then placed in the inclined arm of the trench with its covered opening 25 at the upper end. The stove or oven member is then placed over the incinerator member with its edges resting upon the surface of the ground and with its front edge resting upon the upper surface of the incinerator box. The boiling plates constituting the fire box casing are then assembled in L-shape

about the rear and one side of the oven member over the transverse portion and opposite arm of the trench. The bearing edges of the oven and casing members are to advantage made air tight by sealing with any convenient and suitable material as earth, sand, mud, clay, mortar, or the like. Any space between the casing section 10 and the oven may be filled in like manner. The trench extends forward slightly in front of the fire box opening to facilitate introduction of fuel. If the casing 8, 9, 10 is not to be used for cooking, then a layer of earth, sand or other insulating material may be applied thereupon, to prevent waste radiation of heat.

When the range is to be used for cooking purposes, particularly the oven, the damper 32 in the incinerator stack is closed and the oven damper 31 is opened, whereby the hot gases will be caused to circulate through the gas passages of the oven and impart their heat thereto.

When it is desired to destroy garbage the dampers are reversed, whereby the flame and hot gases are directed downward through the opening 24 in the rear end of the incinerator and caused to pass over the liquid 35 and solid material 36 to be evaporated or incinerated, and thence up the incinerator stack 30.

When the oven is being used, and the oven damper is wide open therefor, the incinerator damper may be left open to a slight extent, sufficient to cause a limited draft upward through the incinerator, so as to avoid any possibility of gases from the incinerator rising through the opening 24 at the rear and passing through the oven. Ordinarily there is sufficient leakage in the incinerator damper and connections to provide for this slight draft, even when the incinerator damper is wholly closed.

It will be seen that this improved range is adapted for a wide variety of uses, including general heating in cold weather, and baking and boiling operations, as well as destroying waste products such as garbage. It has been found in practice that a range such as herein described and about four feet square will readily provide for the cooking for a company of soldiers, and that all garbage and refuse may be disposed of by operating the incinerator attachment for about two hours after each meal. The materials to be incinerated are introduced at the front end through the opening normally closed by the cover 26. Any liquids not held absorbed by the solid materials flow down to the lower end and collect under the fire inlet 24, where they are subjected to the direct action of intense heat whereby they are quickly evaporated and rendered harmless. The solids are soon reduced to an inert state.

Whenever the range is to be moved or placed in storage the L-casing is disconnected from the oven part and the sections 8, 9 and 10 are separated from one another. 5 The oven member if comprising more than one part is knocked down and the sections nested together. The casing sections 8 and 9 are then placed upon opposite sides of the outer oven section with their cornered ends 10 nesting on the front corners of the oven, as shown in Fig. 2. The latch 14 is then swung across the top and engaged with the inwardly disposed top flanges of sections 8 and 9. The latch thus disposed lies just 15 back of the funnel flange on the oven, as shown in Fig. 2, and prevents said sections from slipping forward. Finally the section 10 is placed across the top, with its door to the rear and with its opposite depending 20 flanges clasping the oven and complementary casing members 8 and 9. When the section 10 is in this position the door 16 depends against the rear wall of the oven and the opening 17 registers with the smoke 25 pipe flange on the oven. In order to secure the parts in this position, the oven is provided in front of and adjacent to said flange with an angle lug or clip 38 which engages the section 10 at the front edge of the aperture 30 17. The door 16 has a slot 39 which registers with a staple 40 on the back of the oven when the parts are thus assembled, and a hasp or hook 41 pivoted on the door 16 engages the staple 40 for locking the section 35 10 in position. The hook pivot 42 is preferably set tight enough to hold the hook 41 at any position to which it may be swung. This arrangement fastens all the parts together, so that there is no need of employing 40 ropes or other fastening means. When a unitary oven is used, as shown in Figs. 5 and 6, the incinerator member is telescoped together and nested within the oven member. Handling of the range when thus 45 packed is facilitated by means of handles 43 and 44 on the oven.

Although a preferred embodiment of this invention and certain modifications thereof have been herein shown and described, it 50 will be understood that no attempt has been made to enumerate or specifically describe all useful forms or embodiments, or all useful applications of this invention, and that numerous details of the constructions shown 55 may be altered or omitted without departing from the spirit of this invention as defined by the following claims.

I claim:

1. A device of the class described, comprising a heat utilizing member having an inlet opening at one side near the bottom and having an outlet opening in combination with an L-shaped burner casing having the outer end of one arm communicating 60 with said inlet opening and the other arm

disposed beside said heat utilizing member and having a fuel feed opening at its outer end.

2. In a device of the class described, the combination of a heat utilizing member having a gas inlet at the rear near the bottom thereof, and an L-shaped casing having one arm extending across the rear of said heat utilizing member and communicating with said gas inlet opening, and having another arm extending along the side of said heat utilizing member and provided with a fuel feed opening at its front. 70 75

3. A device of the class described, comprising an oven having an inlet opening at one side near the bottom and having an outlet opening, and an L-shaped casing having one end communicating with said inlet opening and having a fuel door at its opposite end, said casing being open at the bottom 80 85 and adapted to serve as a cover for a trench adapted to constitute a fire box and combustion chamber for said oven.

4. A device of the class described, comprising a rectangular oven member having a gas inlet opening at the rear, and an L-shaped casing extending across the rear and along one side of said bottom section and having a fuel door at its front end for the purpose specified, said L-shaped casing being made up of separable sections adapted 90 95 to be nested with said oven member.

5. A device of the class described, comprising a rectangular oven and an L-shaped trench cover, said cover comprising a plurality of sections adapted to nest with said oven, one of said sections being adapted to overlap the others when nested with the oven, and fastening means acting between the oven and said one section for securing 100 105 all of said sections together.

6. In a device of the class described, a fire box and combustion chamber in combination with and communicating with a heat utilizing member disposed alongside thereof, an incinerator disposed beneath said heat utilizing member and communicating with the combustion chamber, and means adapted for controlling the discharge of gases from said combustion chamber to either said heat 110 utilizing member or said incinerator. 115

7. A field range adapted for military camps, comprising an oven member arranged and adapted for utilizing the heat of gases of combustion, in combination with a fuel burning member disposed beside said oven member and communicating therewith for the discharge thereto of its products of combustion, and a garbage incinerating member adapted to be disposed beneath said oven member, said apparatus being adapted and arranged for resting substantially upon the surface of the ground above and about a suitable trench formed to supplement said fuel burning member and to receive said 120 125 130

- garbage incinerating member, and adjustable means for directing the products of combustion either through the oven member or through the garbage incinerating member.
8. In a device of the class described, a garbage incinerating member comprising a relatively long and narrow box of water tight and fire proof construction, open at one end on its upper side to receive hot gases of combustion, and provided at its opposite end on its upper side with an opening adapted to receive material to be incinerated, a cover for the opening on said opposite ends, said box also having an opening adjacent to the cover equipped end for the discharge of gases.
9. In a device of the class described, a garbage incinerating member comprising a relatively long and narrow box of water tight and fire proof construction, open at one end on its upper side to receive hot gases of combustion, and provided at its opposite end on its upper side with an opening adapted to receive material to be incinerated, a cover for the latter opening, said box also having an opening adjacent to the cover equipped end for the discharge of gases, said box comprising a plurality of telescopic sheet metal sections adapted for collapsing into compact space for transportation and storage.
10. As an attachment for a field range for military camps, a garbage consumer comprising a long, narrow, water tight and fire proof box adapted for disposition in an inclined trench beneath the main body of the range, said box having an opening in the upper side at its lower end for communication with the combustion chamber of the range, and also having a covered opening at
- its forward upper end adapted to facilitate the introduction of garbage to be destroyed, said box having at its upper end an upwardly projecting discharge gas flue, and damper means associated therewith for 45 regulating the draft.
11. A device of the class described, comprising a heat utilizing member having a gas flue with its inlet at the rear adjacent to the bottom, an L-shaped combustion chamber casing having one of its arms disposed across the rear of said heat utilizing member and communicating with the inlet of said flue and having its other arm disposed at one side of said heat utilizing member, in 50 combination with an angular trench having arms beneath and corresponding with the arms of said casing, said trench being open in front for the admission of fuel.
12. A device of the class described, comprising a U-shaped trench formed in the ground, one arm of said trench being extra deep at its inner end and shallow at its outer end and having its bottom inclined accordingly, in combination with an incinerator member disposed in the inclined arm, a heat utilizing member disposed over said incinerator member, a combustion chamber casing of L-shape disposed over the opposite arm and cross connecting portion of said 55 trench, and means for directing the fire box gases either through said incinerator member or through said heat utilizing member.

Signed at New York this 10th day of October 1913.

OSCAR J. CHARLES.
